OFFICE EQUIPMENT FOR HANDLING LARGE
BINDERS

Frank Stanley Schade, Holyoke, Mass., assignor
to National Blank Book Company, Holyoke,
Mass., a corporation of Massachusetts

Substituted for application Serial No. 658,732,
April 1, 1946. This application October 23,
1947, Serial No. 781,513

1 Claim. (Cl. 45—60)

1

This invention relates to improvements in office equipment for handling large binders, books, etc., for example large books of record as are commonly used in accounting departments, and statistical organizations. Its purpose is to provide, simple, inexpensive office equipment by which the user can arrange to handle any number of large books efficiently. This application is a substitute for abandoned application Serial No. 658,732.

Apparatus will be disclosed below by way of an example with some modifications to show how the invention may be practiced. The example will be understood best by a preliminary discussion of the purpose for which it is made.

In the prior art it is common to place a set of large books, telephone directories for example, upside down on a support, to hinge each book at one end of its back portion. To use a selected book it is merely swung 90° on its hinge, it is thus swung out of the set in position to be opened out horizontally, and when opened is right side up for reading. Reversely it is closed and swung back to the stack of the set. Various forms of book handling office equipment embody a similar arrangement which is quite convenient. The trouble with the prior art so far as I know it is this. In office equipment the structure is expensive particularly when adapted to handle many books. Also the equipment is not flexible with respect to handling substantially less or more books than that for which the particular equipment is designed. The present invention provides for an improved line of equipment for the user particularly adapted to the relation of his variable requirements.

The many advantages of the particular apparatus here disclosed will be apparent from the following description especially in relation to its flexibility in handling a small or large number of binders.

In the drawings:

Fig. 1 is a perspective view of the assembled apparatus for practicing the invention;

Fig. 2 is a fragmentary view of the hand portable unit of Fig. 1 to show the hinging action and structure;

Fig. 3 is a fragmentary view to show details of construction;

Figs. 4 and 5 are fragmentary views to show a modified form of construction; and

Figs. 6 and 7 are magnified views on line 6—6 of Fig. 4 to show steps in removing a single binder in the modified form.

The apparatus for handling a single group of large books of records is shown in perspective by Fig. 1 with a group of three large visible index binders, hingedly mounted on a hand portable platform 2. The platform has at each end vertically looped book ends 3 to support the binders

between them in stacked position, the second book-end being against the book at the opposite end. End walls 4 of the platform 2 are provided with portions cut away to form handle holds 5. The platform is mounted on wheels 6, Figs. 2 and 3, the axles of which are fixed at one end in side wall 7 and at the other end in the offset position of a bracket 8 attached to the inside of wall 7 as by rivets and offset around the wheel.

10 The platform is mounted on a rectangular tray 9 for lengthwise movement of the platform in the tray guided by longitudinal tracks 10 provided adjacent each side wall 11 of tray 9. The tray 9 is longer than the platform 2, its length being determined by the practical aspects of the particular varied uses for which it may be desired. I have found that a tray from three to five times the length of the platform is most convenient for taking advantage of the flexibility in the use of the assembled equipment.

15 In use the tray is placed crosswise in front of a user's position at a desk, counter or other working surface. It is set far enough back of the user's position to permit the swinging of any book directly onto his working surface for making entries in the binder or for reference purposes. Platform 2 is limited in its rolling movement on the tray in front of the user, by end walls 12. Two similar hand portable platforms 2 may be set upon the same tray or as will be described below a unit with a larger number of books may be combined in use with the tray.

20 Each binder 1 is pivoted on its back panel edge to the edge of the longitudinal platform side wall 7, by the hinge construction shown. The binders, as indicated in Fig. 1, are mounted with the reading matter upside down. Hinge plates 14 are fastened as by rivets 15 to the back panel of each binder. In the example shown, plate 14 is formed with a slight curvature to fit the curved back panel of the binder. The plate is also offset, Fig. 2, to permit the edge of the binder back to nest snugly in the plate for reenforcement. In use the binder is swung on its hinge in a 90° arc to lie substantially horizontal, Fig. 2, on a working surface, not shown, and opened in position with the printed matter right side up for reading.

25 The plate 14 has spaced portions 16 rolled at the ends in cylindrical form. Portions 16 are mated with similar spaced portions 17 of a hinge plate 18 attached to side wall 7. Two pintles 19 are threaded one from each end of plate 18 through the mating cylindrical portions 16 and 17 to form the hinge pinle means of the construction.

30 By this construction, see Fig. 3, any one of the binders can be removed without chance disarrangement of the mating parts of another. A handle 20, Fig. 2, at the outer end of each pinte 19 is for withdrawing its pinte out of engagement with the cylindrical portions. When the pintles

are inserted the handles are removably snapped into a slot 21 cut in the surface of platform 2. The removal of one pintle 19 allows removal of the book adjacent the end of that pintle, the other pintle keeping the central binder hinge parts in hinged alignment. Partial removal of both pintles permits removal of the middle binder with no displacement of hinge parts on the end binders.

The assembly of the hand portable binder set on platform 2 on the tray 9 shown as an example of the invention, is adapted for the handling of many large books in separate units of three binders each. On a tray proportioned to the platform as shown in the drawing of Fig. 1, a second platform with three binders, may be added, thus making a total of six binders in the assembly. Each one of the binders may be moved crosswise of the working surface at one side of the tray and centered in front of the user, pulled down on its hinge, and opened for inspection without doing more than slide the platform unit lengthwise of the tray for opening it in the position most convenient for the user. The other binders are conveniently out of the way, readily available and at the user's fingertips. No special type of working surface is required. The tray may be placed on any flat surface where the work in connection with the binders is to be done. The hand portable set may be picked up by its handles, or the book ends if preferred, and placed in a storage vault or book shelf with hundreds of similar portable units. When several persons are using more or less frequently the same or similar sets of records contained in the books, a tray can be provided on the working surface of each user at several different locations. The ready adaptability of the apparatus for the different requirements of any individual business office will be appreciated from the flexible character of the assembled combination as office equipment. The handling of this class of large books will be facilitated by the comparatively inexpensive apparatus as shown. And the efficiency of large business organizations will be increased by its use.

In Figs. 4 through 7 I have shown a modified form of hinge structure which is used with a portable set containing more than three binders. The hinge in either form of binder could of course be pivoted by one pintle pin. However, for the convenient removal of any one binder from the set I provide means to do this without the difficulty of rethreading the pin with other hinge elements out of alignment. In the larger sets separate pintles 19' for each of the individual binders are held in the half cylindrical portions 17' of hinge bar 18'. A slide 22 is held on bar 18' in bayonet slots 23 by pegs 24 attached to bar 18'. The upper edge 25 of slide 22 retains the pintles in hinging relation. A single binder is removed by shifting the slide by a finger piece 26 at each end of slide 22 from the position shown by Figs. 4 and 6 to a lower position in the slots 24 as in Figs. 5 and 7. The binder is then swung outwardly on its corner edge, lowered and its individual pintle 19' withdrawn from the hinging structure. The other binders seated on the platform 2 hold their pintles 19' in the portions 17'.

The combination of the tray and portable set of books, shown in the examples of the disclosure, is a definite contribution in the art of office equipment by virtue of its flexibility in handling the large heavy books as stated. The saving over

prior types of office equipment now known to me is found not only in the initial and maintenance costs of the equipment itself but more directly in operational conveniences as compared to other operating movements with the prior art book handling apparatus.

Having disclosed my invention, I claim:

In office equipment for books, the combination of several large binders, each binder having an offset hinge plate construction along a corner edge at the back with an outer portion thereof overlying the back portion and an inner hinge portion providing a pivotal axis spaced from said corner edge inwardly of the binder, a platform having depending longitudinal side walls and wheels carried thereby inwardly of said walls and under the platform, book ends, one along each end edge of the platform to removably position the binders on the platform, a hinge construction on one longitudinal side wall of the platform and providing a pivotal axis along said side wall, means to removably mate said hinge construction of the binders to said hinge construction of the platform and providing a pivot for each binder on a side wall of the platform to hingedly bind the books and platform for any book stacked between the book ends to be swung out to be opened, individually closed, and returned to stacked position, the assembly of the aforesaid parts formed in one hand portable unit of binders, stacked between book ends, supported, and hinged to one side of the wheeled platform, such unit being formed for a hand transport between a point of storage and a point of use, a cooperating assembly of a tray longer than said platform and having upstanding side and end edges, lengthwise tracks on said tray to removably receive and guide the platform wheels for lengthwise movements on the tray and cross wise movement of a book user's position at a desk or table top working surface, said tracks being open and accessible from above to permit the platform to be lifted vertically on and off the tracks, the tray being adapted for positioning crosswise in front of such user's position and back of his working surface to leave room for swinging out a binder from the platform, the aforesaid parts forming the hand portable unit of binders and the said tray construction being adapted for a system in which a user may have any number of binders stored, arranged in hand portable sets, each set between book ends, stacked on a small wheeled platform, hinged to the platform, and placed when desired for use on said tray with tracks for the user's convenient use when desired at his working space as stated.

FRANK STANLEY SCHADE.
